CASKET CONSTRUCTION

William L. Slaughter, Green Township, Hamilton County, Ohio, assignor to The Crane & Breed Casket Company, Cincinnati, Ohio, a corporation of Ohio

Application July 20, 1956, Serial No. 599,130

5 Claims. (Cl. 27—6)

This invention relates to metal caskets and is more particularly directed to the construction of casket bodies from soft, untempered, enduring metal sheets of light gauge, particularly zinc.

An object of this invention is to provide a casket having a body constructed of soft, untempered, enduring metal sheets of light gauge, particularly zinc.

Another object of this invention is to provide a casket body of the above character having a lid hinged to one wall thereof, said wall being so constructed that the wall to which the lid is hinged does not slump or bow into permanently distorted and useless condition.

A further object of this invention is to provide a casket body of the character in which an elongate, rigid, anti-bow member is secured in flatwise face-to-face engagement with the under side of the top flange portion of the wall to which a lid is hinged and in which an elongate member having at least one longitudinal fold extends adjacent the intermediate panel portion of the wall and has its ends secured by solder to the opposed faces of the under side of the elongate, rigid, anti-bow member, and the bottom flange portion, respectively, the upper end of the elongate member being secured to the anti-bow member adjacent a hinge member.

A further object of this invention is to provide a casket body of the above character having side walls and end walls formed from sheet zinc and having hollow molding-like top and bottom portions joined by an intermediate panel portion, the walls having inwardly projecting top and bottom flange portions in substantially parallel relation to each other, the walls meeting in mitre joints and being soldered together, a corner member being secured to the panel portions of adjoining abutting walls adjacent the hollow bottom molding portion, the corner members extending downwardly to an integral flange lying in flatwise abutment to a portion of the bottom flange and being secured thereto, the corner member substantially precluding splitting of the mitre corner seam as a result of the forces applied through impact or collision of an object with the casket body adjacent said seam.

A further object of this invention is to provide a casket body of the above character in which the hollow, molding-like portion is provided with an elongate, tempered, stiffening member secured to the body to preclude inward or outward bowing of the upper hollow molding portion of the casket wall to which the lid is hinged.

A further object of this invention is to provide a casket of the above character in which lid latch actuating means are mounted in the wall thereof adjacent to but spaced from the top lip flange.

A further object of this invention is to provide a casket of the above character having a plate lying in face-to-face abutment with a portion of the casket wall adjacent the top lip flange thereof, casket latch actuating means extending through registering apertures provided in said wall and plate, the casket latching means being actuatable by rotation of portions thereof, the plate member

2

serving to preclude permanent distortion of the body wall adjacent the latch actuating means incident to operation thereof.

A further object of this invention is to provide a casket body of the above character in which a member of elongate, L-shape in section is secured in flatwise abutment with the intermediate panel portion of the side wall and with its foot portion secured in flatwise engagement to the upper face of the bottom wall flange, the member being connected to external casket-carrying handles, whereby the intermediate panel portion of the wall is protected from permanent distortion incident to carrying of the casket by said handles by reason of a portion of the load being transferred to the L-shaped member.

The above and other objects and features of this invention will in part be obvious and will in part be apparent to those having ordinary skill in the art to which this invention pertains, from the following description, and the drawing, in which:

Figure 1 is a view in front elevation of a casket embodying the present invention;

Fig. 2 is a fragmentary view in end elevation of the casket illustrated in Fig. 1, portions thereof being broken away to more clearly show the co-operation of the casket wall, plate and latch actuating means;

Fig. 3 is a view in perspective of a fragmentary portion of a casket body, partly in section taken adjacent the latch actuating means;

Fig. 4 is a fragmentary view in perspective, partially in section of a portion of the rear wall of the casket body illustrated in Fig. 1;

Fig. 5 is a fragmentary view in perspective partly in section, illustrating the construction of lower corners of the casket body, and

Fig. 6 is a fragmentary view in perspective, partly in section, showing one of the lower corners of a casket body constructed in accordance with another embodiment of this invention.

Long known as a metal which will long endure when buried in the earth, zinc has not been used as extensively as this quality might suggest. Iron and its alloys and the more expensive metal copper and its alloys have been far more extensively used in this field. Iron and its alloys generally used are less enduring than zinc when buried in the earth as a casket. Copper and its alloys are more expensive than zinc which endures about as well when buried. However, while caskets can be fabricated from sheet steel and from sheet copper by the same or similar tools and techniques and of substantially the same structure, such has not been the case with zinc.

Zinc is soft, easily deformed by forces of a magnitude such as a casket is often exposed to during normal handling between manufacture and placement in the earth. The joints or seams of steel and of copper caskets are welded or brazed but those of zinc caskets, because of the temperatures involved, can only be soldered with a soft solder. The soft soldered joint is much weaker than the joints used in the steel and the copper caskets. As a result, for example, the corner seams of zinc caskets often open under the force of impacts encountered in their transportation. Also an otherwise conventionally constructed sealer casket, but constructed of sheet zinc, will often become useless if left with the lids in opened position, particularly if exposed to the sun's rays. The wall of the body to which the lid member or members are hinged will frequently sag or slump, as well as bow inwardly or outwardly, making closing and sealing of the casket impossible.

Even when the casket has survived to the point where the casket lid is closed, it frequently is damaged in latching. Many casket lid latches are actuated by rotation of

a member by means of a key or crank. Some of the torque forces are transmitted to the thin casket wall by which the actuating means are at least in part supported, effecting permanent bulging or dimpling of the casket wall adjacent the actuating means. Similar permanent distortion of this portion of the casket is at times the result of cocking or misalignment of the key or crank while the latches are being actuated to lock the lid into the closed position.

The casket carrying handles are conventionally mounted on the casket wall. However, the sheet zinc walls are often permanently distorted by the loads imposed upon them when the casket is carried by means of handles so mounted.

A half-couch sealer type casket 7 of conventional appearance, shown in Fig. 1, is an illustrative embodiment of my invention. The casket 7 comprises a body 8, a pair of lids 9 each secured by means of hinges 10 (shown in Fig. 4) to the rim portion of body 8 and means 11 for actuating latches for securing the lids 9 in closed relation to body 8.

Body 8 has side walls 12, 13, end walls 14, 15 and bottom 16. A portion of side or rear wall 12 is shown in vertical section in Fig. 4. Wall 12 has an intermediate panel portion 17 above which the wall is fabricated in the form of a hollow upper molding portion 18. The upper molding portion 18 has an upright outer face portion 19, a bottom portion 20 joining the upper edge of panel 17 and the lower edge of face portion 19. The top face portion 21 of molding 18 is the upper horizontal lip face of casket body 8. Top face portion 21 extends from the upper edge of face portion 19 horizontally inwardly, past the plane of panel 17 extended, to a depending flange 22. A groove 23 extends longitudinally of portion 21 parallel to and spaced from the edges thereof.

Wall 12 is fabricated to form an hollow lower molding portion 24 adjacent the lower edge of panel 17. As shown in Fig. 4, molding 24 has an upper face portion 25 joined to panel 17 by a quarter round portion 26 and to the bottom face portion 27 by vertical face portion 28. Bottom face portion 27 extends from the lower edge of vertical face portion 28 to the lower edge of an integral upright portion 29 which is parallel to the plane of panel 17 and between that plane and vertical face portion 28. A second upright portion 30 joined to portion 29 by horizontal portion 31 is parallel to portion 29 and spaced from the plane of panel 17 extended, which plane is intermediate said portions 29 and 30. The second upright portion 30 is spaced from the plane of panel 17 by a distance equal to or greater than the distance by which flange 22 is spaced from that plane. A flange 32 extends from the lower edge of portion 30 substantially parallel to and away from portion 27. While wall 12 has been described above, the walls 13, 14 and 15 have corresponding parts.

The walls 12, 13, 14 and 15 meet in soldered miter joints at the corners of the body 8. Bottom 16 is placed in engagement with flange portion 32 of wall 12 and the co-planar corresponding portions of walls 13, 14 and 15.

I have found that the tendency of the corner seams of body 8 to break open under impact forces adjacent the bottom corners 33 is overcome when a corner member 34 is provided. As shown more clearly in Fig. 5, corner member 34 has portions 35 and 36 joined together at fold line 37. Portions 35 and 36 are also joined to flange portions 38 and 39 at fold lines 40 and 41, respectively. Portions 35 and 36 adjacent the upper edges thereof are secured in flatwise face-to-face engagement with the respective panel portions 17 of walls 14 and 15 meeting at right angles in a mitre joint as shown in Fig. 5. The corner formed at fold line 37 nests in the angle formed by the intermediate panel portions 17 of the casket body walls. As shown, the corner member 34 has its flange portions 38 and 39 resting upon the upper face of horizontal portion 31 and soldered thereto.

Turning again to Fig. 4, hinge plates 42 are secured

to wall 12 by providing apertures in portion 19 subjacent to edge 53 through which portions of hinge members 42 may extend in an inclined attitude into abutment with the under side of groove 23 in portion 21 at 68. The hinge portions 42 may be soldered in position, the solder serving to secure the hinge portion in position and to seal any portion of the opening remaining unfilled by the hinge member 42. The spaces between members 42, 21 and 43 are filled by solder. To preclude horizontal bowing of portion 21 I provide an anti-bow member 43, a bar or strip of stiff metal such as band iron 43 and secure same as by soldering to the under side of portion 21 adjacent groove 23 and flange 22.

The member 43 extends substantially full length of the inner edge of groove 23 in wall 12 with its ends preferably disposed nearer to walls 13 and 15 than the hinge portions 42 nearest to said walls. The anti-bow member 43 serves to preclude bowing of the wall 12 inwardly or outwardly.

To preclude slumping or sagging of wall 12, I provide 20 a plurality of elongate members 44 each having a longitudinal fold line 45. The longitudinal edges of each member 45 substantially contact the inner face of panel portion 17 and its ends are in abutment with the upper face of portion 31 and the under face of member 43, as 25 shown in Fig. 4. An elongate member 44 is provided opposite each hinge plate portion 42. As shown, the member 44 extends upright and is secured by means of solder to the anti-bow member 43 and portions of wall 12 with which it is in contact, namely, portions 31 and 17. 30 It may also be secured to flange portion 22. I have found that the elongate members 44 may be fabricated from the same sheet zinc material used in fabrication of the walls 12, 13, 14 and 15.

As shown in Fig. 1, the handles or rails 46, by means 35 of which the casket 7 may be carried, are secured to mounting brackets 47 having screw studs 48. As shown in Fig. 4, I provide in the interior of casket body 8 opposite each bracket 47, a second or interior handle bracket having an upright plate portion 50 and an horizontal flange portion 51 integrally joined together at fold line 52. Plate portion 50 lies in flatwise abutment with intermediate panel portion 17 of wall 12 while the flange portion 51 lies in flatwise abutment with the upper face of portion 31 of wall 12. Portions 50 and 51 are secured by 40 means such as solder to the abutting portions of casket wall 12. The screw studs 48 extend from bracket 47 successively through registering apertures in a resilient gasket (not shown) interposed between bracket 47 and the outer face of wall 12, wall 12 and portion 50 into engagement with retaining nuts 49. Nuts 49 are drawn up tightly to 45 clamp the gasket member (not shown) and member 50 between brackets 47 and nuts 49. Thus, when the casket is carried by means of handles or rails 46, plates 50 are loaded in tension and preclude imposition of forces sufficiently great to effect permanent distortion upon wall 12.

Referring now to Figs. 1, 2 and 3, I provide a rigid plate member 56 in flatwise abutment with the inner face of portion 19 of wall 13 adjacent the location in which the latch actuating means are mounted. As shown in the drawings, edge 55 of plate 56 abuts the underside of portion 21 and edge 57 thereof abuts the upper side of portion 20 of wall 13. Plate member 56 may be secured in the position shown by suitable means, such as drops of solder at points along its margin in a fashion frequently referred to as "tacking." Suitable sealing means may be provided to preclude fluid entering the casket between the inner face of wall portion 19 and plate 56. I have found solder may be used to seal the margin or edges of the plate 56 to the inner face of wall 14. Registering apertures are provided in plate 56 and portion 19 of wall 13. A thimble 58 is snugly received therein with its annular flange portion 59 engaging an annular washer 60 which in turn engages plate 56, when thimble nut 61 is drawn 65 up tightly. A depending tab or hanger bracket 54 co-

operates with thimble 58, supporting same at a point spaced from plate 56 and wall portion 19. A rotatable shaft 62 extends through thimble 58 and suitable sealing means such as washers, packing, or the like (not shown) are provided between members 58 and 62 to effect a fluid-tight seal therebetween. The outer exposed end of shaft 62, as shown in Fig. 3, may be adapted to co-operate with a key or wrench, by suitable means, such as a hexagonal recess or socket 63. The latch mechanism illustrated in the drawings comprises an elongate, reciprocatable bar 64 having a plurality of wedge-shaped tongues 65 adapted to engage depending stirrup-like keeper members 66 secured to the lid portions 9. The tongues 65 of elongate bar 64 serve as wedges co-operating with stirrup-like keeper members 66 for wedgingly drawing the lids 9 toward casket body 8. A suitable gasket member 69 is preferably provided between the opposed faces of wall portions 21 and the opposed face portion of the lids 9, the gasket 69 serving to effect a seal between lids 9 and casket body 8, as the latch mechanism is actuated. To actuate the latch mechanism, a plurality of rack teeth 70 are provided on bar 64 in engagement with pinion gear 71 secured to shaft 62 for rotation in unison therewith. Thus, when shaft 62 is rotated by means of key or wrench 73 (shown in Fig. 2), latch bar 64 is reciprocated to latch or unlatch the lids 9 of casket 7.

Turning again to Fig. 4, it will be noted that bottom 16 has portions 72 thereof displaced upwardly to provide channel or groove-like indentations in the lower face thereof, in which skid members 75 are mounted by Z-bars 76 soldered to the under side of bottom 16 and extending into engagement with grooves provided in skid member 75. I prefer that the dimension A of skid member 75 is greater than the distance B, in order that the skid members 75 engage the supporting surface upon which casket 7 is placed.

In Fig. 6 is shown a corner construction for a casket body 8 constructed in accordance with another embodiment of this invention. The casket body 8 is similar to that already described in all details of construction, other than the corner structure, and, accordingly, other portions of the casket body 8 have not been shown in detail. The casket body 8 has a side wall 82, an end wall 83, and a bottom 84. The side and end walls are each provided with a vertical-faced base section 85, an inwardly extending horizontal portion 86, a quarter-round portion 87, and an upwardly extending face 88. Edges of the side and end walls are mitred and soldered together at the edge 89. The walls and bottom may be formed of zinc.

The corner portion of the wall of the casket body is strengthened by an angle-shaped brace 91 of steel, or the like. The brace 91 extends from the bottom 84 along the inner wall of a floor rib 92 to immediately below the fold line between the quarter-round portion 87 and the upwardly extending face 88. The brace 91 is soldered to the wall and to the bottom as indicated in the drawings, and serves to strengthen the corner section of the casket body to prevent splitting of the corner seam in the event of any substantial stresses at the corner.

Having described the invention, it will be apparent to those having ordinary skill in the art to which this invention pertains, that various modifications and changes may be made in the illustrated embodiment, without departing from the spirit or the scope of the appended claims.

Therefore, what is claimed as new and desired to be secured by Letters Patent is:

1. A casket body of soft sheet metal, the walls of said body being formed to provide hollow molding-like top and bottom portions and an intermediate panel portion, said walls having a bottom flange, the central portion of

the bottom flange being of inverted channel form to provide an upstanding longitudinal rib intersected by the plane of the panel portion, a support member of L-shape in vertical section secured in face-to-face engagement with and across said panel portion and downward to said rib, the foot flange of said support member being secured to said rib, handles, handle-securing means co-operating with said support member and wall panel, whereby said casket may be carried without permanent distortion thereof.

2. A sheet zinc casket body having a rear wall member formed to provide hollow molding-like top and bottom portions and an intermediate panel portion, said wall member having a bottom flange and a top lip flange, at least one hinge member secured to and supported on said top molding-like portion for hinging a lid to said body, at least one elongate member having at least one longitudinal fold line, said elongate member extending between said bottom flange and said top lip flange adjacent a hinge member and being secured to said flanges and to said intermediate panel portion whereby sagging of the rear wall member under the weight of the lid when raised, is precluded.

3. A sheet zinc casket body having a rear wall member formed to provide hollow molding-like top and bottom portions and an intermediate panel portion, said wall member having a bottom flange and a top lip flange, a longitudinal tempered metal member soldered to the under side of said top lip flange inside said body, at least one hinge member secured to and supported by said top molding-like portion for hinging a lid to said body, at least one elongate member extending between said bottom flange and said top lip flange adjacent a hinge member and being secured to said flanges and to said intermediate panel portion whereby slumping and bowing of the rear wall member is precluded.

4. A casket body of formed sheet zinc metal, said body having side walls and end walls formed to provide hollow molding-like lower wall base portions meeting in mitre corner joints, each of said wall portions having a bottom flange, the central portion of which is formed to provide an upstanding longitudinal channel rib disposed between said molding portion and a casket bottom engaging portion, said mitre joint being soldered on the inside of the body, a corner member folded along a vertical line and being of L-shape in vertical section, the fold line of said corner member being adjacent the mitre joint of an end wall and a side wall, said corner member being soldered adjacent its upper edge to portions of said end wall and side wall adjacent the upper portion of said molding-like wall base portions, the foot of the corner member resting upon and being soldered in flatwise engagement with the upper face of the channel rib, whereby splitting of the mitre corner seam spaced from said corner member is substantially precluded.

5. A casket body of formed sheet zinc metal, said body having side walls and end walls formed to provide hollow molding-like lower central base portions meeting in mitre corner joints, each of said wall portions having a bottom flange, said mitre joint being soldered on the inside of the body, a corner member of L-shape in vertical section mounted on said bottom flange and extending upwardly therefrom to the wall portion, the upper portion of the corner member being soldered to the end wall and to the side wall, the foot of the corner member resting on and being soldered to the bottom flange, whereby splitting of the mitre corner seam spaced from said corner member is substantially precluded.
